WILLIS E. ROYS, OF RICHMOND HILL, NEW YORK.

THERMOSTATIC VALVE.

1,262,261.

Specification of Letters Patent. Patented Apr. 9, 1918.

Application filed April 17, 1916. Serial No. 91,556.

To all whom it may concern:

Be it known that I, WILLIS E. Roys, a citizen of the United States of America, residing at 637 Walnut street, Richmond Hill, 5 Long Island, New York, have invented a new and useful Thermostatic Valve, of which the following is a specification.

My present invention relates particularly to heating systems and the general objects 10 of the invention are to provide a simple and efficient form of a thermostatically controlled valve for regulating the flow of fluid such as steam or hot water.

Special objects of the invention are to 15 effectively insulate the thermostatic mechanism from the supply pipe and radiator so that said mechanism will be influenced by the surrounding air conditions rather than by the temperature of the pipe which supplies the fluid or the radiator to which the pipe is attached.

Another special object is to provide simple, accurate and easily regulatable means 20 for setting the thermostat to operate at different temperatures.

A further special object is to prevent leakage around the valve operating stem.

In the accomplishment of the foregoing objects, I secure the thermal insulation of 25 the thermostat mechanism from the steam or other supply pipe by the interposition of baffles between said pipe and the thermostat, and I obtain a simple and at the same time accurate adjustment of the thermostat by 30 means of a member bearing on the thermostat and having a threaded engagement in a backing or supporting member. Leakage at the valve stem is guarded against by the interposition of a relatively small flexible 35 metallic diaphragm arranged to be engaged by the valve operating member.

Indications are preferably provided for facilitating the adjustment of this bearing member, a convenient and preferred method 40 being to flatten one side of the threaded shank of said adjustable member and to place graduations on the flattened side of said shank.

Other features and details of construction 45 will appear as the specification proceeds, attention being directed to the accompanying drawing forming part hereof and wherein

I have illustrated the invention embodied in a practical form.

In this drawing:

Figure 1 is a front view of my improved 55 thermostat valve construction, partly broken away and showing a portion of the supply pipe to which the device is connected.

Fig. 2 is a vertical sectional view taken 60 substantially on the plane of the line 2—2 of Fig. 1 and showing the manner in which the valve may be connected with the radiator of a hot water or steam heating system.

Fig. 3 is a plan view of the device taken 65 substantially on the plane of the line 3—3 of Fig. 1.

Fig. 4 is an enlarged perspective view of the adjustable regulating member.

The body of the device is made up of a 70 shell composed for the most part of a base plate 7 and a backing plate 8, the two plates being secured together in spaced relation as by means of the screw studs 9.

Hingedly secured to one of these plates, in 75 this case the base plate 7, by means of a spring hinge 10, is a valve operating lever 11 having a point 12 bearing on the diaphragm 13 of the controlling valve structure 14.

Engaged between the valve operating lever 11 and the backing plate 8 is the thermostat 14' made up in the illustration of a pair of corrugated spring disks united at 80 their edges and forming a chamber filled with a readily expansible fluid.

The adjustment of the thermostat is obtained, according to my invention, by means of a member 15 bearing on the outer side of the thermostat and having a threaded shank 90 16 engaged in the supporting plate 8. It will be evident that by adjusting this bearing member inward or outward the thermostat may be shifted in respect to the valve operating lever and so may be caused to 95 actuate said lever at different temperatures. The accurate adjustment of the bearing member is provided for in the illustration by flattening one side of the threaded stem of said member, as indicated at 17, and providing graduations thereon such as indicated at 18, said graduations having numerals or other convenient markings.

The controlling valve is shown as made

up of a valve 19 carried by stem 20 and arranged to engage a valve seat 21. The inner end of the valve stem engages the inner surface of the diaphragm 13 substantially opposite the bearing point 12 of the valve operating lever, and a relatively light spring 22 is preferably provided exerting its force to open the valve.

The controlling valve is connected with a 10 pipe 23 leading from the boiler or other source of supply and is connected in the present instance with a radiator 24 of a steam or hot water heating system through the medium of a short pipe 25 and an 15 elbow 26.

The piping connections 25 and 26, are preferably made up as a unit with the controlling valve and the thermostat mechanism so that the whole may be handled as a 20 single member and be placed in service by simply connecting the upper end of the controlling valve with the supply pipe and the elbow with the radiator or other device. This arrangement is provided for in the 25 present illustration by securing the base plate 7 to ears 27 on the elbow by means of screws 28 and to similar ears or lugs 29 on the controlling valve body by means of screws 30.

30 The thermostatic mechanism is thus in effect supported from the pipe line which supplies the heat to the radiator. To prevent the thermostatic mechanism from being influenced disadvantageously from such 35 pipe line and to insure that the thermostat will be governed by surrounding temperature conditions within the room, I interpose a baffle plate 31 between the base plate 7 and the pipe line which supports the base 40 plate and the mechanism carried thereby. This baffle may, as indicated, be held in place by the screws 28-30 which secure the base plate to the piping, and washers 32 of leather or other poor heat conductors are 45 preferably interposed at opposite sides of the baffle between the baffle and the piping and the base plate respectively.

Additional baffles 33 are provided between the base plate and the valve operating lever, 50 these baffles being shown secured in place by screws 34 separated from the base plate by thermal insulating washers 35.

These baffles prevent conduction of heat from the pipe line to the thermostat and serve to produce a circulation of air which 55 practically frees the thermostat from the influence of the pipe line and radiant heat from the radiator.

The diaphragm 13 with which the operating lever engages should be relatively small 60 to present a small area to the pressure within the controlling valve, and at the same time, this diaphragm should possess considerable flexibility to allow for a full opening and closing movement of the valve. To meet these 65 requirements I preferably make the diaphragm of a thin disk of silver-copper alloy and corrugated as indicated in Fig. 2. This construction gives the necessary flexibility in a small size diaphragm. 70

What I claim is:

1. In combination with a pipe and a valve controlling passage of fluid through said pipe, a base plate supported by said pipe off to one side of said pipe, a thermostat 75 supported by said base plate, operating connections from said thermostat to the valve aforesaid and thermal insulating baffle plates between the supporting pipe and the base plate and between the base plate and the thermostat.

2. In combination with a base plate, a supporting plate spaced therefrom a valve actuating lever hingedly secured to one of said plates, a thermostat engaged between 85 the supporting plate and the valve operating lever, a screw having a threaded shank adjustably engaged in the supporting plate and a head bearing upon the thermostat and baffle plates interposed between the base 90 plate and the valve operating lever.

3. A thermostatic valve unit comprising in combination a controlling valve, an elbow and piping connecting said valve and elbow, a base plate secured to said valve and elbow, 95 a backing plate secured in spaced relation to said base plate, a valve operating lever between said plates and hingedly connected to one of said plates, a thermostat interposed between the backing plate and said valve operating lever and a bearing member adjustably engaged in said backing plate and bearing on said thermostat. 100

WILLIS E. ROYS.
